DESIGN FOR A KITCHEN CABINET

Hercheal Wood Miller, Davenport, Iowa

Application January 26, 1945, Serial No. 117,620

Term of patent 14 years

(Cl. D33—13)

To all whom it may concern:

Be it known that I, Hercheal Wood Miller, a citizen of the United States, residing at Davenport, in the county of Scott and State of Iowa, have invented a new, original, and ornamental Design for a Kitchen Cabinet, of which the following is a specification, reference being made to the accompanying drawing, forming a part thereof.

In the drawing:

Fig. 1 is a perspective view of a kitchen cabinet embodying my present design; and

Fig. 2 is a side elevational view of this cabinet.

The bottom surface of the upper section of the cabinet is a plane, flat surface.

I claim:

The ornamental design for a kitchen cabinet, substantially as shown and described.

HERCHEAL WOOD MILLER.
